UNITED STATES PATENT OFFICE.

WILLIAM SIEBENMORGEN, OF WESTFIELD, NEW JERSEY, ASSIGNOR TO C. & C ELECTRIC COMPANY, A CORPORATION OF NEW JERSEY.

WELDING APPARATUS.

No. 918,921.

Specification of Letters Patent.

Patented April 20, 1909.

Application filed February 23, 1907. Serial No. 358,802.

To all whom it may concern:

Be it known that I, WILLIAM SIEBENMORGEN, a citizen of the United States, residing at Westfield, New Jersey, have invented certain new and useful Improvements in Welding Apparatus, of which the following is a clear, full, and exact description.

My invention relates to an apparatus which is useful in electric welding, such for example as fusing the edges of two metal parts together.

Heretofore electric welding has been accomplished by drawing an arc between a carbon terminal and the object to be welded, the heat of the arc fusing the metal parts together. In carrying out this operation a voltage greatly in excess of that needed for the maintenance of the arc has been used with a resistance in series to prevent too great rush of current at time of making contact. The great waste of power in the above method is apparent. In my invention I prefer to use a pressure not exceeding that of the voltage across the terminals when the arc is drawn to its working length, and to provide means for automatically controlling the voltage between the terminals.

My invention will be set forth in the claims.

30 In the drawings which show a preferred form of my invention; Figure 1 represents a diagram of connections, and Fig. 2 a detail of an alternative construction.

1, 2, represents an electric transformer, 35 which in the present case is a direct-current motor-generator. The motor 1 is connected to suitable mains 3 and 4 constituting the primary circuit, and the generator 2 is rotated by the motor, as is common in such rotary 40 transformers. The generator 2 is in this case the source of electro-motive force for the arcing or secondary circuit.

5 and 6 are two electric terminals between which the arc is adapted to be drawn, 5 representing in this case two metal pipes which are to be welded together at the joint 7. The terminal 6 is preferably a freely movable carbon point provided with a suitable insulated handle 8, so that the workman may 50 move it by hand, as desired. In order to reduce the voltage across the terminals to prevent a too great flow of current when the terminals are in contact, I preferably provide a resistance in the circuit. 9 is such a resistance in the main circuit from the generator,

to the arcing terminals, and is preferably ohmic and of such an amount as will prevent a too great rush of current when the operator brings the terminal 6 in contact with the work just previous to drawing the arc, which he does by moving the terminal 6 away to such a distance as will draw the arc to the desired length, as indicated, for example, by the dotted lines at 10. It will be obvious that, as the two terminals are moved apart, 65 the resistance of the circuit will increase on account of the space necessary to be bridged by such arc, and it is therefore desirable to automatically raise the voltage across said terminals to maintain the arc as the terminals 70 are separated in drawing the arc, and, when a starting resistance is used, to cut out some or all of such resistance in order to compensate for such increase of resistance (by the arc) in the circuit, and in the drawings I have 75 provided means for automatically varying said resistance 9 substantially inversely proportionally to the resistance of said arc, that is, to the increase in resistance between the two arcing terminals while said arc is playing 80 between them. This I preferably accomplish by providing a switch for automatically cutting out said line resistance as the resistance of said arc rises as a consequence of the gradual removal of the movable terminal 85 from the work. In the construction illustrated in Fig. 1, such a switch is indicated at 11, and it will be obvious that when such switch is raised so as to bridge the stationary contacts 12 and 13, the resistance 9 will be 90 substantially removed from the circuit because of the short-circuit formed around it by wire 14 and switch lever 15. The switch lever 15 is in this case a hand-operated lever which may be moved so that more or less of 95 said resistance will be cut out by switch 11. In order to control the time of operation of such switch 11, I preferably provide a normally-open shunt 16, 17, around the arcing terminals with a solenoid 18 therein of high 100 resistance, which solenoid may consist of many turns of fine wire, as will be evident to any one skilled in the art.

In order to control the closing of the shunt switch 22 I have provided means controlled by the current in the main arcing circuit, which may be another solenoid 19 of relatively low resistance compared with that of solenoid 18.

20 and 21 are springs for retracting the 110

switch arms 11 and 22 when the solenoids are deenergized or the current through them drops to a predetermined amount. Such springs, solenoid 19, and switch 22, are therefore one embodiment of a means for automatically restoring the circuit to normal condition on the rupture of said arc.

It will be obvious that when the workman desires to draw the arc, he needs merely to bring the terminal 6 in contact with the work, which will cause current to pass through the solenoid 19 and raise the switch lever 22, thus bridging the contacts 23 and 24, and, as the movable terminal leaves the work, an arc will be formed between them, the resistance 9 preventing a too great rush of current. As the terminal 6 is moved farther away, the resistance of the arc, that is, the resistance to the current passing between said two terminals through the arc, will increase, thus causing an increasing amount of current to pass through the shunt until such time as the shunt solenoid 18 is energized sufficiently to raise its core and bridge the contacts 12, 13. Such solenoid 18 may obviously be wound to operate at any predetermined time. Such shunt and solenoid therein constitute one form of means for operating the resistance switch, and is obviously controlled by the resistance of the arc in the sense that it operates when said resistance rises to a certain amount.

The solenoid 19 is obviously one form of a construction which is controlled by the current in the main circuit to automatically close the shunt circuit when the resistance between the arc terminals drops to a predetermined amount—such, for example, as when the two terminals are brought into contact—and will permit spring 20 to open the same when the arc is ruptured. Such rupture of the shunt circuit will also cause the resistance 9 to be inserted in the main circuit, because the shunt solenoid 18 will be deenergized, and the springs 20 and 21 will open both switches, thus restoring the parts to their normal condition.

While I have, in Fig. 1, shown a construction in which the whole of the starting resistance 9 is cut out simultaneously it may be desirable to cut said resistance out gradually, and in Fig. 2 I have shown an alternative construction in which the pivoted switch arm 25 is connected to the core of the shunt solenoid 26 by a bell crank lever 27 and link 28, so that as the current in said solenoid rises it will gradually move the switch arm to the left, thus gradually cutting out the starting resistance 9 instead of cutting the same out as a whole. Such alternative construction in Fig. 2 would obviously also vary the resistance substantially inversely to the resistance of the arc.

It will be observed that in both figures of the drawing the voltage across the terminals

is automatically raised to maintain the arc as the resistance resulting from drawing the arc rises. In Fig. 1 this is accomplished when the switch 11 closes, thus cutting out the resistance 9 all at once, and in Fig. 2 when the current operates the solenoid 26. By such expression I do not mean to confine myself to necessarily cutting out all the line resistance at once as this may obviously not be necessary, and in fact it may be in some cases more desirable to cut it out gradually, as illustrated in Fig. 2. It will also be observed that the resistance switch is automatically controlled by the variation (preferably both the increase and decrease) in resistance of the arc and is adapted to similarly vary the voltage across the arcing terminals so as to maintain the arc in spite of such variation in resistance of the arc.

I have used in practice a generator which generates a current of from 450 to 600 amperes at 75 volts pressure, and the solenoid 18 was wound to operate when the voltage across the arcing terminals was substantially 50. It will be obvious that no definite amount of turns of resistance in the solenoids 18 and 19 need be given for a clear understanding of the invention by an electrician, as it will be obvious that the solenoid 18 may, in the construction shown in the drawings, be merely wound to such a resistance as will, after the arc is ruptured, cut down the current sufficiently to deenergize solenoid 19.

31 is a movable hand switch for cutting out more or less of the turns of solenoid 18, as may be desired.

As a means of protecting both circuits, particularly the primary, from an abnormal rush of current, I have provided a circuit controller in such secondary circuit, which, in the present instance, is a circuit breaker 29, and I control this by the current in the primary circuit by, preferably, a solenoid 30 in said primary circuit. In case the total watts used by the dynamo exceed a certain amount, there will obviously occur an abnormal rush of current in the primary or motor circuit, which would energize the solenoid 30 sufficiently to operate the circuit breaker, said solenoid being obviously wound to operate only in case of such overload. The switch brush 29 is carried on a hand lever 32, and spring 33 is provided to open the switch when the retaining lever is released upon energizing the solenoid 30.

While in the foregoing I have shown and described one means of carrying out my invention, I do not limit myself to such construction, as it will be obvious that many changes may be made from the construction herein illustrated without departing from my invention as claimed.

What I claim is:

1. In a welding apparatus in combination,

a circuit comprising a source of electromotive force and two terminals one of which is movable and manually operable and between which an arc is adapted to be drawn, means in said circuit before said terminals are brought into contact which, when said terminals are brought into contact, operates to prevent a too great flow of current across said terminals, and a circuit controller adapted to automatically raise the voltage across said terminals to maintain the arc as the arc resistance rises through the separation of said terminals.

2. In a welding apparatus in combination, a circuit comprising a source of electromotive force and two terminals one of which is movable and manually operable and between which an arc is adapted to be drawn, means in said circuit before said terminals are brought into contact which, when said terminals are brought into contact, operates to prevent a too great flow of current across said terminals, and a circuit controller adapted to automatically raise the voltage across said terminals to maintain the arc as the arc resistance rises through the separation of said terminals, and means to automatically restore said circuit to its original condition on the rupture of said arc.

3. In an electric welding apparatus, a circuit comprising a source of electro-motive force and two terminals one of which is movable and manually operable and between which an arc is adapted to be drawn, a resistance normally in said circuit before said terminals are brought into contact and adapted to prevent a too great rush of current when said terminals contact, and means controlled by the current for automatically varying said resistance substantially inversely proportionally to the resistance of said arc.

4. In an electric welding apparatus, a circuit comprising a source of electro-motive force and two terminals one of which is movable and manually operable and between which an arc is adapted to be drawn, a resistance normally in said circuit, and means for automatically cutting out said resistance as the resistance of said arc rises.

5. In an electric welding apparatus, a circuit comprising a source of electro-motive force and two terminals one of which is movable and manually operable and between

which an arc is adapted to be drawn, a resistance in said circuit, means for automatically cutting out said resistance as the resistance of said arc rises, and means for automatically reincluding said resistance in the circuit on the rupture of said arc. 55

6. In an electric welding apparatus, a circuit comprising a source of electro-motive force and two relatively movable terminals between which an arc is adapted to be drawn, a resistance in said circuit, a shunt around said arc, and means for automatically cutting out said resistance as the current in said shunt rises. 60

7. In an electric welding apparatus, a circuit comprising a source of electro-motive force and two relatively movable terminals between which an arc is adapted to be drawn, a resistance in said circuit, a shunt around said arc, means for automatically cutting out said resistance as the current in said shunt rises, and means adapted to automatically open said shunt and re-insert said resistance 75 on the rupture of said arc.

8. In an electric welding apparatus, an arcing circuit comprising a source of electro-motive force, an ohmic resistance, and two relatively movable terminals between which an arc is adapted to be drawn, a shunt around said arc, a switch in said shunt and means controlled by the current in said arcing circuit to automatically close said switch 80 when the resistance between said terminals drops to a predetermined amount and open the same when said arc is ruptured, and means for automatically cutting out said ohmic resistance as the resistance of said arc 90 rises. 85

9. In an electric welding apparatus, a circuit comprising a source of electro-motive force and two relatively movable terminals between which an arc is adapted to be drawn, a resistance in said circuit, a shunt around said arc and automatic means for gradually decreasing said resistance as the current in said shunt rises. 95
